UNITED STATES PATENT OFFICE

ARTHUR R. HAVENER, OF WAYLAND, MASSACHUSETTS, ASSIGNOR TO JUDSON L. THOMSON MANUFACTURING CO., OF WALTHAM, MASSACHUSETTS, A CORPORATION OF MASSACHUSETTS

HOLDER AND CARRIER FOR A RIVETING MACHINE

Application filed August 7, 1930. Serial No. 473,679.

This invention relates particularly to an improved holder and carrier for a riveting machine, the object of the holder and carrier being to receive and position a piece of flat material slotted longitudinally thereof and having one end forming a hook, the said holder and carrier also being adapted to position a two-pronged rivet in alignment with the slot in said hooked piece of material, whereby the hooked piece of material may be attached to another piece of material by said rivet through the co-operative action of a driver and anvil with said hooked piece of material and two-pronged rivet interposed therebetween.

The object of the present embodiment of this invention is to attach a hooked piece of flat material to a moth-proof bag adjacent the opening thereof, whereby the two edges 20 of the bag opening may be held together, the hooked member being slidable upon the rivet whereby it is attached to one side of the bag adjacent the opening.

The invention consists in the improved holder and carrier hereinafter set forth in the specification and particularly pointed out in the claims, and in the combination thereof with a driver and anvil and mechanism to impart a reciprocatory motion to the 30 driver and holder and carrier.

Referring to the drawings:—

Fig. 1 is a side elevation of the holder and carrier of this invention, a portion of a driver and raceway being illustrated in connection therewith.

Fig. 2 is a rear elevation of the parts illustrated in Fig. 1, the driver and raceway being omitted.

Fig. 3 is an underneath plan of the parts illustrated in Fig. 1, the raceway and driver being omitted.

Fig. 4 is a view similar to Fig. 1 with the right hand holder plate and its supporting spring removed, a two-pronged rivet being illustrated in position on said plate and also a hooked plate.

Fig. 5 is a side elevation of the other holder plate viewed in the opposite direction to that 50 in which Fig. 4 is viewed.

Fig. 6 is a sectional elevation taken on line 6—6 looking toward the left in Fig. 1.

Fig. 7 is a view in elevation similar to Fig. 4, but with the parts in the relative positions occupied thereby at the end of the clinching of the rivet in the material, the hooked plate being shown in connection therewith in section.

Fig. 8 is a perspective view of a two-pronged rivet adapted to be used in the device of this invention.

Like numerals refer to like parts throughout the several views of the drawings.

In the drawings, 10 is a holder and carrier slide. A pair of oppositely disposed spring arms 11 and 12 are fastened to the slide 10 by a bolt 13 and nut 14. These spring arms are offset at their lower ends and have fastened to their lower ends a pair of oppositely disposed plates 15 and 16, the plates 15 and 16 being fastened respectively to the spring arms 11 and 12 and interposed therebetween.

The plate 15 is provided in its lower face with a groove 17 which has a recessed or inclined wall 18. The plate 16 also has in its under face a groove 19 with a similar recessed side wall 20. The two grooves 17 and 19 combine to form a guideway 21 which is adapted to receive and hold a flat piece of material 22 which is bent at one end to form a hook 23. The said flat piece of material 22 is provided with a slot 24 extending longitudinally thereof.

The plates 15 and 16 are spaced apart to form a chamber 25 adapted to receive a two-pronged rivet 26. The inner faces of the plates 15 and 16 are recessed to form a pair of oppositely disposed inclined ridges 27 and 28 respectively, and these inclined ridges support the two-pronged rivet 26 upon the opposite sides of its head 29, as particularly illustrated in Fig. 6. The rivets are delivered into the chamber 25 by a raceway 30 in a manner well-known to those skilled in the art.

The rivet 26 and the hooked plate 22 are driven out from between the holder plates 15 and 16 by a driver 31, Figs. 1 and 7, the prongs of the rivet passing downwardly through the slot 24 through a sheet of material 32 and through a disc 33 on the under

side of said sheet material and then the prongs 34 of the rivet are clinched by engaging an anvil 35 and are returned into the disc 33, see Fig. 7.

5 The hooked plate 22 is inserted in the guideway 21 as illustrated in the drawings, by hand, and the said hooked plate is positioned longitudinally thereof with relation to the rivet driver 31 by a stop 36 which is fastened 10 by screws 37 to the plate 16.

The general operation of the mechanism hereinbefore specifically and to some extent in general described is as follows: The two-pronged rivets 26 descend the raceway 30 and 15 the lowermost rivet in the raceway enters the chamber 25 between the plates 15 and 16 of the rivet holder, sliding into the chamber 25, and assuming the position illustrated in Fig. 4, the opposite edges of the rivet resting 20 upon the ridges 27 and 28 in the plates 15 and 16. The hooked plate 22 having been placed in position, as illustrated in Figs. 1 and 4, the driver 31 descends and the lower end thereof passes into the chamber 25 and contacts with the top 29 of the rivet 26. The carrier slide and the holder are then pushed down by the driver until the carrier slide engages a stop above the material 32 which is positioned upon the anvil 35, whereupon 25 when the driver descends still further the two-pronged rivet will be thrust downwardly in the chamber 25, the two plates 15 and 16 spreading apart to allow the said rivet to pass downwardly. The prongs of the rivet pass 30 through the slot 24 in the hooked plate 22 and then through the material 32 and through the disc 33 positioned between the material 32 and the anvil 35.

The driver continues to push the rivet 35 downwardly until the prongs 34 are clinched by the anvil 35 into the disc 33. During the latter part of the descent of the driver, the hooked plate 22 will be forced out from between the plates 15 and 16 by the head of the rivet 26 as it is driven downwardly by the driver and thus attached to the upper face of the material 32, all as illustrated in Fig. 7. The driver then moves upwardly and the carrier slide with the rivet and hooked plate 50 holder also move upwardly being carried upwardly by a spring 38.

It will be understood that the hooked plate 22 remains suspended on the holder plates 15 and 16 with its opposite edges positioned in 55 the grooves 17 and 19 until driven out of said grooves and from between said plates by the rivet 26 and driver 31. Due to the fact that the grooves 17 and 19 are deeper than the ridges 27 and 29, when the rivet is first driven 60 downwardly relatively to the plates 15 and 16 by the driver, the plates 15 and 16 while separated are not separated sufficiently to allow the opposite edges of the hooked plate to pass downwardly and out from between said 65 plates 15 and 16.

The driver 31 is operated by suitable mechanism and its downward descent operates the carrier slide 10 in a manner well known to those skilled in this art and after the general manner described in United States Letters 70 Patent to J. E. Perrault, Machine for setting rivets, No. 879,895, patented February 25, 1908.

I claim:

1. A holder and carrier for a riveting machine having, in combination, a slide, a pair of oppositely disposed spring arms fast to said slide and spaced apart, and a pair of oppositely disposed plates fast to the lower ends of said arms, the under faces of said plates being provided with grooves, which form a guideway adapted to receive and hold a flat piece of material. 75

2. A holder and carrier for a riveting machine having, in combination, a slide, a pair of oppositely disposed spring arms fast to said slide and spaced apart, and a pair of oppositely disposed plates fast to the lower ends of said arms and spaced apart to form a chamber adapted to receive a two-pronged rivet, the inner faces of said plates being recessed to form a pair of oppositely disposed inclined ridges upon which the head of a two-pronged rivet may rest and whereby said rivet is held in an inclined position. 85

3. A holder and carrier for a riveting machine having, in combination, a slide, a pair of oppositely disposed spring arms fast to said slide and spaced apart, and a pair of oppositely disposed plates fast to the lower ends of said arms, the under faces of said plates being provided with grooves, which form a guideway adapted to receive and hold a flat piece of material, said plates being spaced apart to form a chamber adapted to receive a two-pronged rivet, the inner faces of said plates being recessed to form a pair of oppositely disposed ridges upon which the head of a two-pronged rivet may rest. 100

4. A holder and carrier for a riveting machine having, in combination, a slide, a pair of oppositely disposed spring arms fast to said slide and spaced apart, a pair of oppositely disposed plates fast to the lower ends of said arms, the under faces of said plates being provided with grooves, which form a guideway adapted to receive and hold a flat piece of material, and a stop at one end of said guideway adapted to position said piece of material on said holder and carrier. 110

5. A holder and carrier for a riveting machine having, in combination, a slide, a pair of oppositely disposed spring arms fast to said slide and spaced apart, and a pair of oppositely disposed plates fast to the lower ends of said arms, the under faces of said plates being provided with grooves having an inclined side wall, said grooves combining to form a guideway adapted to receive and 120

hold a flat piece of material with its edges abutting against said recessed side walls.

6. A holder and carrier for a riveting machine having, in combination, a slide, a pair of oppositely disposed spring arms fast to said slide and spaced apart, and a pair of oppositely disposed plates fast to the lower ends of said arms, the under faces of said plates being provided with grooves, which combine to form a guideway adapted to receive and hold a flat piece of material with a slot extending longitudinally thereof, said plates being spaced apart to receive a two-pronged rivet, the inner faces of said plates being recessed to form a pair of oppositely disposed ridges upon which the head of a two-pronged rivet may rest with its prongs positioned in alignment with said slot.

7. A riveting machine having, in combination, a slide, a holder embodying a pair of oppositely disposed plates spring mounted on said slide and recessed to receive a piece of flat material with a slot extending longitudinally thereof, said holder having a chamber between said plates adapted to receive and position a two-pronged rivet therein with said prongs in alignment with said slot.

In testimony whereof I have hereunto set my hand.

30 ARTHUR R. HAVENER.
